Pendant bead in Sea Fire Set chalcedony necklace, identified by arrows on actual p. 3, identified at bottom as page (12 of 59), on "Magpie Magic: Jan. 2008" internet site, 6 pages, printed on Mar. 24, 2009.*

Primary Examiner—Elizabeth A Albert

(74) Attorney, Agent, or Firm—Shook, Hardy & Bacon LLP

(57) **CLAIM**

The ornamental design for a marker, as shown and described.

DESCRIPTION

FIG. 1 is a perspective view of a marker showing the new design;

FIG. 2 is a front elevational view thereof;

FIG. 3 is a right side elevational view thereof, a left side elevational view thereof being a mirror image thereof;

FIG. 4 is a rear elevational view thereof; and,

FIG. 5 is a top plan view thereof.

The broken lines are included for the purpose of illustrating portions of the marker that are environmental structure that form no part of the claimed design.
